UNITED STATES PATENT OFFICE.

CHARLES L. LONSINGER, OF WALHONDING, OHIO.

SLED.

1,256,707.

Specification of Letters Patent. Patented Feb. 19, 1918.

Application filed May 21, 1917. Serial No. 170,005.

To all whom it may concern:

Be it known that I, CHARLES L. LONSINGER, a citizen of the United States, residing at Walhonding, in the county of 5 Coshcocton and State of Ohio, have invented certain new and useful Improvements in Sleds; and I do declare the following to be a full, clear, and exact description of the invention, such as will enable others skilled 10 in the art to which it appertains to make and use the same.

My invention has for its object to provide a number of novel features of construction whereby bob sleds and the like may be manufactured cheaply yet rigidly, and with this general object in view, the invention resides in the novel features of construction and unique combinations of parts to be herein-after fully described and claimed, the descriptive matter being supplemented by the accompanying drawings which constitute a part of this application and in which:

Figure 1 is a side elevation of the improved sled;

Fig. 2 is a top plan view thereof;

Fig. 3 is an enlarged longitudinal section on the plane of the line 3—3 of Fig. 2;

Fig. 4 is a vertical transverse section on the plane of the line 4—4 of Fig. 2;

Fig. 5 is a perspective view of one of the runner braces;

Fig. 6 is a transverse section on the plane indicated by the line 6—6 of Fig. 3; and,

Fig. 7 is a sectional perspective showing a modified form of runner.

In the drawings above briefly described, the numerals 1 and 1' have reference to two forms of runners, each runner 1 consisting of a metal channel bar 2 with its channel 40 disposed upwardly, said bar having longitudinal tread flanges 3 projecting outwardly from its lower corners and flush with its lower side. A filler 4 of wood is positioned in the channel of the bar 2 and an inverted 45 channel-shaped metal guard 5 receives said bar therein to protect said filler.

The runner 1' illustrated in Fig. 7, consists of an inverted channel bar 2' having longitudinal tread flanges 3' extending outwardly from its lower corners and secured to a suitable shoe 6 by means of which a wood filler 4' is protected.

One of the two forms of runners described, is preferably employed since both types 55 thereof are light yet durable, but it is to be

understood that any preferred runners could well be employed.

Disposed above the runners are two longitudinally extending sills 7 which are secured at their front ends to the corresponding and 60 upturned ends of said runners, said sills receiving thereon the ends of transverse bolsters 8 preferably carrying sockets 9 for the reception of stakes 10. The bolsters are preferably formed of wood with the sockets 9 65 secured thereto as shown, but metal construction could well be employed should occasion so demand.

Horizontal bolster plates 11 are interposed between the sills 7 and bolsters 8 and are 70 inset in the former as shown most clearly in Fig. 3, the inner ends of said plates being folded outwardly upon themselves to form attaching ears 12, secured by bolts or the like 13 to said bolsters, and then inclining 75 downwardly and outwardly to form braces 14 having feet 15 which rest on the runners, said braces being preferably, though not necessarily, of hollow formation. If this construction is followed, the parts 11, 12, 80 14 and 15 may well be formed of a single length of piping flattened adjacent its ends but it will be obvious that other constructions may be employed if desired.

Interposed between the feet 15 and the 85 sills 7 are vertical spacing sleeves 16 which serve to support said sills, washers 17 being preferably located between said sills and sleeves, in order to provide an increased bearing area for the former. The sleeves 90 16 receive therein vertical bolts 18 which also pass through the runners, the feet 15, washers 17, and the bolsters 8 and plates 11, the heads of said bolts being countersunk in the runners while the nuts 19 at the upper 95 ends thereof are preferably inset in the bolsters 8.

The draft device to be described is connected to the front ends of the runners and sills, whereas the rear ends of the latter will 100 in most cases extend beyond the rear bolster 8 and will be connected by a transverse bar 20 secured thereto by bolts 21. These bolts also serve to anchor the upper ends of inclined braces 22 which extend to the runners 105 and are provided with flat feet 23 positioned beneath the rearmost of the feet 15.

The tongue 24 is provided at its rear end with a loop 25 through which passes a short length of piping 26 upon whose ends re- 110

ducers 27 are threaded. Other short lengths of piping 28 of numerous diameters, are threaded together as shown, the smaller fitting into the larger and the largest being 5 threaded into the reducers 27. Braces 29 extend outwardly and rearwardly from the tongue and are provided with eyes 30 at the ends of the outermost lengths of pipe 28, said eyes being also in contact with the inner 10 sides of the sills 7. A rod 31 passes through said eyes and through the several lengths of pipe and at its ends is received in appropriate bearings 32 at the front end of the sled. The bolt 33 which secures the braces 15 29 to the tongue, also serves as a pivot for the doubletree 34, and in order to prevent canting of said bolt, it preferably passes through a rigid yoke 35 carried by the braces 29 and located beneath the tongue 24.

20 By the construction employed for securing the ends of the bolsters 8 to the sills 7 and for supporting said sills from the runners, all parts are rigidly joined and braced, and the use of mortise and tenon joints and the 25 like, is eliminated, thus providing a much stronger structure and one which may be made of more delicate proportions. The two types of runners shown and described are both simple, inexpensive, and light in 30 weight, yet they will be highly efficient and durable. The same may be said of the means for attaching the tongue. On account of these advantages, the several features of construction shown and described, are preferably embodied in the improved sled. It 35 is to be understood, however, that within the scope of the invention as claimed, numerous changes may be made.

I claim:

40 1. A sled comprising runners, longitudinal sills above said runners, transverse bolsters supported at their ends on said sills, transverse bolster plates interposed between said bolsters and sills and having their inner 45 ends folded outwardly to form attaching ears and then inclined downwardly and

outwardly to form braces extending to the runners, said braces having feet resting on said runners, fasteners passing through said bolsters and said ears, vertical spacing sleeves interposed between said feet and said sills for supporting the latter, and vertical bolts passing through the runners, the feet, the sleeves, the sills, and the bolsters and bolster plates. 55

2. A sled comprising runners, longitudinal sills above said runners, transverse bolsters supported at their ends on said sills, transverse bolster plates interposed between said bolsters and sills and inset in the latter, 60 said plates having their inner ends folded outwardly to form attaching ears and then inclined downwardly and outwardly to form braces extending to the runners, said braces having feet resting on said runners, fasteners passing through said bolsters and said ears, vertical spacing sleeves interposed between said feet and said sills for supporting the latter, and vertical bolts passing through the runners, the feet, the sleeves, the sills, 70 and the bolsters and bolster plates.

3. A sled runner comprising a metal channel having integral outstanding tread flanges, a filling of wood in said channel, and a metal protector over the portion of 75 said filling at the open side of the channel.

4. A sled runner comprising a metal channel bar with its channel disposed upwardly, said bar having longitudinal tread flanges extending horizontally from its lower corners and flush with its lower side, a filling of wood in said channel, and an inverted channel-shaped metal guard receiving said channel bar therein to protect said filling. 80

In testimony whereof I have hereunto set 85 my hand in the presence of two subscribing witnesses.

CHARLES L. LONSINGER.
